US00D986873S

(12) **United States Design Patent** (10) **Patent No.:** **US D986,873 S**
(45) **Date of Patent:** **** May 23, 2023**

(54) **CASE FOR MOBILE TELEPHONES**

(71) Applicant: **Yiqiang Zhang**, Guangdong (CN)

(72) Inventor: **Yiqiang Zhang**, Guangdong (CN)

(73) Assignee: **Guangzhou Eastmate Plastic Product Co., Ltd.**, Guangdong (CN)

(**) Term: **15 Years**

(21) Appl. No.: **29/798,637**

(22) Filed: **Jul. 9, 2021**

(30) **Foreign Application Priority Data**

Jun. 23, 2021 (CN) 202130390683.7

(51) **LOC (14) Cl.** **14-03**

(52) **U.S. Cl.**

(57) **CLAIM**

The ornamental design for case for mobile telephones, as shown and described.

DESCRIPTION

FIG. 1 is a bottom, rear perspective view of case for mobile telephones showing my new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom, front perspective view thereof;

FIG. 9 is a rear perspective of the case for mobile telephone in an alternate configuration showing the ring holder flipped upward;

FIG. 10 is an enlarged view of the portion of FIG. 1 outlined by the dot-dash broken line labeled 10;

FIG. 11 is an enlarged view of the area labeled 11 outlined by the dot-dash broken line in FIG. 1;

FIG. 12 is an enlarged view of the area labeled 12 outlined by the dot-dash broken line in FIG. 1; and,

FIG. 13 is an enlarged view of the area labeled 13 outlined by the dot-dash broken line in FIG. 1.
